COMPENSATED TRANSFORMER

Wilbur T. Harris, Southbury, Conn., assignor to The Harris Transducer Corporation, Woodbury, Conn., a corporation of Connecticut

Original application January 22, 1954, Serial No. 405,614, now Patent No. 2,776,416, dated January 1, 1957. Divided and this application July 13, 1955, Serial No. 521,745

13 Claims. (Cl. 336—181)

My invention relates to an improved core and winding construction for electromagnetic circuit elements, and this application is concerned particularly with transformer embodiments of said invention. This application is a continuation-in-part of my application Serial No. 318,720, filed November 4, 1952 (now Patent No. 2,776,417), and is a division of my application Serial No. 405,614, filed January 22, 1954 (now Patent No. 2,776,416).

It is an object of the invention to provide improved devices of the character indicated.

It is a specific object to provide an improved transformer core and winding construction having the basic virtues of toroidally wound cores, without requiring the elaborate fabrication techniques necessary with toroidal windings.

It is another specific object to provide an improved transformer construction in which stray hum or other pick-up may be completely and inherently compensated for and, therefore, neutralized.

Other objects and various further features of novelty and invention will be pointed out or will occur to those skilled in the art from a reading of the following specification in conjunction with the accompanying drawings. In said drawings, which show, for illustrative purposes only, preferred forms of the invention:

Fig. 1 is a simplified longitudinal sectional view through a transformer incorporating features of the invention; and

Figs. 2, 3, and 4 are similar views of further embodiments.

Briefly stated, my invention contemplates a new core and winding construction employing what may be termed a toroidal magnetic core, thereby providing a generally toroidal flux path. In application to transformers, input and output helical-signal windings are coupled to the core path and to the stray-flux path, and compensating windings are coupled to the stray-flux path to the exclusion of or effectively independently of the core path. The compensating windings are differentially connected to their respective signal-winding counterparts and have substantially the same number of turns, so that any coupling to the stray-flux path (whether it be in the input or primary circuit, or in the output or secondary circuit) will be completely neutralized, and coupling by way of the core will, in effect, be exclusively promoted. In one general form, represented by Figs. 1 and 3, the compensating windings are physically located radially inside the signal windings. In the other general form, represented by Figs. 2 and 4, the compensating windings are physically located radially outside the toroidal flux path and, therefore, radially outside the signal windings.

Referring to Fig. 1 of the drawings, my invention is shown in application to a transformer having electrically independent input and output circuit connections 10—11 for an input winding 12 and an output winding 13. The windings 12—13 are coupled to each other solely by way of the flux path circulating in the core, and in accordance

2

with the invention, said flux path is toroidal. The toroidal flux path may be established by elements of magnetic material and is shown to utilize an inner elongated cylinder 14, an outer elongated cylinder 15, and two end-closure plates 16—17. The cylindrical members 14—15 may be of magnetic-oxide ceramic, but are shown sectioned for metal and may simply be helically developed laminated tubes of transformer iron. The end caps 16—17 are shown as of magnetic oxide ceramic and may be bonded to the tubes 14—15.

The windings 12—13 are developed over the inner tubular core member 14 and are therefore electromagnetically coupled thereto so that, upon application of a signal or voltage at the input 10, flux is caused to circulate toroidally. By toroidal flux circulation, I mean that for a voltage of instantaneous direction determining flux say, from left to right along the inner core member 14, said flux also circulates radially outwardly in the end-closure member 17, from right to left in the outer tubular member 15, and radially inwardly in the end-closure member 16. For voltage of reversed instantaneous polarity, the described toroidal flux is in the reverse directional sense.

Although the windings 12—13 are directly coupled to the toroidal flux path, it is also a fact that they are coupled to any stray flux in which the described device may happen to be immersed, and of course for such stray flux, voltages will be induced so as to alter the effective signal transfer between input and output circuits 10—11. In accordance with the invention, I effectively neutralize such stray-flux effects by providing additional or compensating windings 18—19 having substantially the same number of turns as their signal-winding counterparts 12—13 and disposed for essentially the same coupling to the stray flux, to the exclusion of the toroidally circulated flux in the core. Thus, the winding 18 may be differentially connected to the winding 12 so that signal input at 10 is effectively applied to windings 12—18 in series opposition; thus, the axially inner ends of windings 12—18 may be directly connected, as through the hole shown in core 14, so that a compensated input circuit is presented at 10. In the same manner, the windings 13—19 are differentially connected, and voltage output at 11 reflects the series opposition of windings 13—19; this connection may involve the axially inner ends of windings 13—19, as explained for windings 12—18.

The arrangement of Fig. 2 incorporates essentially the same principles as those described for Fig. 1, except for the fact that the compensating windings 18'—19' are disposed radially outside, rather than inside, the signal windings 12'—13'. Thus, the windings 18'—19' may be developed on the periphery of the outer tubular core member 15, and the inner core member 14' need not be tubular. The dotted interconnections of windings 12'—18' and 13'—19' involved passage of wire through suitable holes (not shown) in core member 15, as for the case of core member 14 in Fig. 1. As explained in connection with Fig. 1, the core members 14'—15' may be of magnetic oxide ceramic, as is the case for the end-closure members 16—17. It will be appreciated that in Fig. 2 any coupling of winding 18' or of winding 19' to the core is, in effect, neutralized so that windings 18'—19' are effectively only coupled to stray flux, whereas windings 12'—13' are coupled both to the toroidally circulating flux in the core and to the stray flux. For voltage of a given polarity applied at input 10', the winding 12' may establish flux circulation from left to right in the inner core member 14', radially outwardly directed flux in the end-closure member 17, flux from right to left in the outer core member 15, and radially inwardly directed flux in the end-closure member 16. For the same voltage, any flux developed by the compensating

winding 18' in the core member 15 will be equally and oppositely opposed by flux similarly developed in the core member 14' so that the winding 18' (and, by the same token, winding 19') cannot account for net flux development in the core.

The arrangements of Figs. 3 and 4 incorporate principles discussed in connection with Figs. 1 and 2, except that the application is to an auto-transformer, rather than to a transformer with electrically independent input and output circuit connections. The core of Fig. 3 may be the same as the core of Fig. 1 and, therefore, the same reference numerals have been employed; likewise, for Fig. 4, the core numerals follow those used in Fig. 2. In Fig. 3, a single signal winding 20 is developed over the inner core member 14, and the input circuit 21 is connected to a fraction of the total number of turns of the winding 20. Since the stray-flux coupling due to winding 20 is determined by the number of turns and not necessarily by the input circuit connection, it is merely necessary to employ a single compensating winding 22 differentially connected to the winding 20 at 23, so that the output at 24 reflects differential combination of voltages induced in the winding 20 and in the winding 22.

The electrical connections in Fig. 4 are essentially the same as those described in Fig. 3, so that primed notation is employed. The only difference is that stray-flux compensation voltages are developed by winding 22' externally of the signal winding 20' rather than radially inwardly thereof as in the case of Fig. 3.

It will be appreciated that I have described relatively simple winding and core constructions lending themselves to mass-production techniques which are already well understood and for which there is a relative abundance of machinery. Every winding described may be developed as a pure helical progression, from wire available on a reel, and without requiring special techniques as is customary with toroidal winding. My construction nevertheless has the inherent advantage of a toroidal winding, in that susceptibility to stray flux (which would otherwise be characteristic of a helically wound construction) is reduced to substantially zero. While it has been possible in the past to avoid these undesirable characteristics by resorting to complex fabrication methods and expensive machinery to create toroidal windings, my construction avoids the need for such complexity and expense.

While I have described the invention in detail for the preferred forms shown, it will be understood that modifications may be made within the scope of the invention as defined in the claims which follow.

I claim:

1. A transformer, comprising magnetic-core means establishing a continuous toroidal flux path; input-winding means including a first winding linked to said flux path and to the stray-flux path through the center of said toroidal path, and a compensating winding differentially connected to said first winding and linked to said stray-flux path to the exclusion of said first-mentioned flux path; and output-winding means including a second winding linked to said first-mentioned flux path and also to said stray-flux path, and a further compensating winding differentially connected to said second winding and linked to said stray-flux path to the exclusion of said first-mentioned flux path.

2. A transformer according to claim 1, in which said two first-mentioned windings have substantially the same number of turns.

3. A transformer according to claim 1, in which said two last-mentioned windings have substantially the same number of turns.

4. A circuit element according to claim 1, in which the number of turns of said input-winding means is different from the number of turns of said output-winding means.

5. In a device of the character indicated, two elongated

generally cylindrical members of magnetic material one within the other and magnetically interconnected at their corresponding ends, whereby a generally toroidal flux path is thereby defined, a first winding in the radial space between said members and therefore coupled to said flux path, a second winding developed along and radially within the inner of said members and therefore not coupled to said flux path, an electrical autotransformer tap connection to an intermediate part of said first winding, and means electrically differentially connecting said second winding in series with one of the ends of said first winding.

6. In a device of the character indicated, two elongated generally cylindrical members of magnetic material one within the other and magnetically interconnected at their corresponding ends, whereby a generally toroidal flux path is thereby defined, a first winding in the radial space between said members and therefore coupled to said flux path, a second winding developed along and radially outside the outer of said members and therefore not coupled to said flux path, an electrical autotransformer tap connection to an intermediate part of said first winding, and means electrically differentially connecting said second winding in series with one of the ends of said first winding.

7. In a device of the character indicated, a core comprising two elongated cylindrical members of magnetic material one radially spaced within the other and magnetically interconnected at their corresponding ends, first winding means in the radial space between said members and therefore coupled to said core, said first winding means comprising separate sets of turns constituting primary and secondary halves of a transformer, second winding means substantially axially coextensive with said first winding means but independent of effective coupling to said core, and means electrically differentially interconnecting said winding means, whereby stray-field effects common to both winding means may be substantially eliminated.

8. A device according to claim 7, in which said separate sets of turns are electrically independent of each other.

9. A device according to claim 7, in which said separate sets of turns are separate parts of the same single winding.

10. In a circuit element of the character indicated, a core-body defining a continuous toroidal magnetic-core path; first winding means including a first winding linked to said core path and to the stray-flux path in which said circuit element may be immersed, and a second winding differentially connected to said first winding; and second winding means including a third winding linked to said core path and also to said stray-flux path, and a fourth winding differentially connected to said third winding; said second and fourth windings being unenclosed by the torus of said path and therefore linked to the stray-flux path to the exclusion of said core path.

11. A circuit element according to claim 10, in which said first and second windings have substantially the same number of turns.

12. A circuit element according to claim 10, in which the number of turns of said first winding means is different from the number of turns of said second winding means, whereby a transformer action is achieved between said winding means.

13. A circuit element according to claim 10, in which said second and fourth windings are radially outside said core path.
